UNITED STATES PATENT OFFICE.

RALPH D. MERSHON, OF NEW YORK, N. Y.

INSULATING-SUPPORT FOR HIGH-TENSION CONDUCTORS.

942,335.

Specification of Letters Patent.

Patented Dec. 7, 1909.

Application filed February 5, 1908. Serial No. 414,308.

To all whom it may concern:

Be it known that I, RALPH D. MERSHON, a citizen of the United States, residing at New York, in the county and State of New York, have invented certain new and useful Improvements in Insulating-Supports for High-Tension Conductors, of which the following is a specification.

One of the important problems encountered in the electrical transmission of power by means of currents of high potentials is that of insulation, and much time and ingenuity have been expended in the endeavor to provide economical and effective insulation for high tension conductors. I have also been led to attack the problem and have devised an insulating conductor-support consisting essentially of a "framed structure" having insulating structural members, so arranged or disposed relatively to each other and to the conductor, that mechanical forces originating in the conductor will be resolved into components acting on appropriate structural members of the framework. In this way mechanical forces in the conductor can be resolved, in the insulating framework, into forces of tension or compression or both, with practically complete elimination of bending moments. Hence the insulating members of the framework have to resist only such strains, to-wit, tension, or compression, as they are best adapted, by the nature of the material composing them, to withstand. At the same time, the form of the insulating members can be such as to entirely eliminate so-called puncturing discharges, which kind of discharge is always fatal to any kind of insulator, rendering it unfit for further use, and to confine all possible discharges to "flash-around" discharges. The latter are almost always fatal to insulators of the ordinary type when the power arc which follows the flash is of any appreciable magnitude, that is, when the current on the line is sufficient to produce a power arc giving off a considerable amount of heat. With my insulator, however, a flash-around discharge, and the power arc following, will in the great majority of cases leave the insulator in good condition for further use.

The invention thus briefly outlined I have claimed broadly in my copending application, Serial No. 374,926, filed May 21, 1907,

now Patent No. 917,785, issued April 13, 1909, describing the invention as embodied in a construction in which the mechanical forces originating in the conductor are resolved into both tension and compression.

The invention which forms the subject of my present application is a species of the generic invention claimed in my application above mentioned but differs from the forms therein illustrated in that in the present case the conductor forces are resolved into components of substantially one kind only, preferably compression forces.

In the annexed drawing I have illustrated the preferred embodiment of the invention, and reference may now be had to the drawing, in which—

Figure 1 is a plan view of the insulating structure. Fig. 2 is a side elevation of the same. Fig. 3 is a detail sectional plan view showing the preferred way of connecting the insulating members to the conductor-supporting device. Fig. 4 is a detail sectional plan view showing the preferred way of connecting the insulating members with the vertical members of the structure. Fig. 5 is a plan view of an important modification, and Fig. 6 is a side view of the same, partly in section. Figs. 7 and 8 are plan and side views of a further modification.

Referring now to Figs. 1, 2, 3 and 4 of the drawing, 1 designates the structure on which the insulating support for the conductor is mounted, for example a cross-arm in the form of a lattice member extending horizontally from a tower or other structure not shown. The base of the insulating framework which supports the conductor 3 consists of side members 4, 5, 6, 7, and a cross member or support 8, all of which in the present case are parts of the lattice member 1. Rising from the corners of the base are upright supporting members 9, 10, 11, 12, preferably provided with integral braces or gussets, as 13.

Extending diagonally inward from the upright supporting members at the tops thereof are four insulating members, 14, 15, 16, 17 preferably cylindrical and petticoated or ribbed as shown, which members are connected to the uprights and to a center piece 18 preferably in the manner hereinafter described. The center piece 18 is the part to which the conductor 3 is secured and consists

preferably of an octagonal plate provided with four upwardly extending ears 19, to which the diagonal members are connected. The conductor may be secured to the center plate in any convenient way, as by clamps 20, as shown. Extending between the center plate and the transverse supporting member 8, is a vertical insulating member 21. Each of the insulating members consists preferably of an elongated cylindrical part, of suitable insulating material, as glass, porcelain, etc., provided at its ends with caps 22, 23, having threaded stems 24, 25 for connection with the center plate and the respective upright or the cross member 8.

Any convenient method may be used for eliminating all or substantially all tensional force, preferably by employing suitable connections between the insulating members 14, 15, 16, 17 and the uprights or between the said members and the center plate. A convenient method of connection for this purpose is shown in Fig. 1, but more clearly in Figs. 3 and 4. On the stem, (Fig. 3), between the nut 26 and the center plate ear 19, that is, on the tension side of the ear, is a pair of spring washers 27, and on the compression side of the ear, between the ear and the cap 22, is a single spring washer 28. Also, I may employ at the outer end of each member spring washers 29, one on each side of the upright, as shown in Fig. 4. At each end of the vertical member 21 is a spring washer 30. These washers 27, 28, 29, 30 also serve as cushions, to relieve the comparatively fragile insulating members from vibration and from injurious shocks due to sudden or violent strains on the conductors, as will be readily understood. In order to permit a slight amount of play, the apertures in the uprights and center plate ears are somewhat larger than the stems 24, 25, and similarly the apertures in the center plate and cross member are larger than the stems on the member 21.

It will now be seen that the mechanical forces in the conductor will be resolved into compression components in the insulating members. Thus the weight of the conductor, and other forces exerted directly downward on the center plate, are taken as compression forces by the vertical insulating member 21. Forces exerted longitudinally of the conductor, say in the direction of the arrow in Fig. 1, will cause the washers 27 on members 14 and 15 to yield, but before these washers can yield enough to cause more than slight tension to be exerted on those members the single washers 28 on members 16 and 17 will yield enough to cause practically all the force to be exerted as compression on the latter members. Similarly, a force acting transversely of the conductor, say toward the right in Fig. 1, will be resolved into compression forces in members 15 and

16. In any case there will be practically no bending strains on the insulating members, since the enlarged openings through which their stems pass permit the necessary play of the parts as the center plate is moved in one direction or another. It is evident that by reversing the spring washers 27 and 28, that is, putting the two washers 27 on the compression side of the ear 19, between the ear and the cap, and the single washer 28 on the tension side, between the ear and the nut, the conductor forces will be resolved into tension components in the insulating members. By putting more spring washers on the tension side the slight tensional force transmitted to the members may be reduced as much as desired.

Another form of the invention is illustrated in Fig. 5, in which tensional forces are entirely eliminated without the use of springs, though springs for cushioning purposes may be used as in Fig. 1. In this case the stems 31 and 32, of members 14^a and 15^a are pivotally connected, as by a bolt 33, and similarly the stems 34, 35, of members 16^a, 17^a are connected by a pivot bolt 36, all these members being connected to the uprights in the manner illustrated in Fig. 4. On the pivot bolts 33, 36, are clevises 37, 38, each having a suitable clamp, 39, by which the conductor 3 is rigidly secured to the clevis. Between the two pairs of members the conductor is slack, as indicated by the loop 40. Beneath the pivotal connections of the horizontal members are vertical insulating members 21^a, 21^b, the upper stems of which are pivoted to the bolts 33, 36. At the cross members 8^a, 8^b, the members 21^a, 21^b have slight play and are preferably provided with spring cushioning washers, as in the case of the vertical member 21 in Fig. 2.

In the construction just described it is evident that any force acting longitudinally of the conductor will produce only compression in the insulating members. Thus a force in the direction of the arrow *a* in Fig. 5 will be resolved into compression components in members 16^a and 17^a, while the play of the member 21^b, at the cross member 8^a and at the joint with the bolt 33, will effectively prevent any appreciable bending movement being exerted on the said member 21^b, which thus receives compression only. On account of the slack loop 40 no force will be transmitted to the members 14^a and 15^a. Similarly, if the conductor spans are bowed out by the wind, say in the direction indicated by the arrows *b*, it is clear that the force which causes the bowing-out will also be resolved only into components of compression in the members, though the compression in members 14^a and 17^a will of course be less than in the others. It will also be clear that wind-pressure can in no case produce tensional forces in the members

unless the spans be bowed out beyond the axes of the members on the same side as the bow, a condition which of course cannot occur in practice.

Still another form of the invention is illustrated in Figs. 7 and 8. In this case the insulating members 14^b, 15^b, and 21^c, are secured rigidly at their outer ends to the uprights and the appropriate cross member, and their inner ends are rigidly connected together, as by being cemented in suitable sockets in a casting 41. The insulating members 16^b, 17^b, and 21^d are similarly connected to their uprights and cross member, and to a similar casting 42. In this construction, as may also be the case, if desired, in the form shown in Figs. 5 and 6, the upwardly extending insulating members are inclined inwardly, as shown, the sockets for receiving the same being inclined to permit such arrangement. The conductor 3, is fastened rigidly to the connecting castings by suitable means, as the clamps 43, preferably as near as possible to the intersections of the axes of the insulating members. A slight amount of slack is left in the conductor between its points of attachment or support, as shown. It is now evident that in this form of the invention as in the form illustrated in Figs. 5 and 6, forces acting on the conductor spans longitudinally, downwardly, or laterally will be resolved into compression components in the insulating members. The weight of the castings 41 and 42 tends to exert tension on their respective horizontal members, since the axes of the upwardly extending members 21^c, 21^d are not exactly vertical; but when the structure is in use, the pull of the conductor, due to its weight, is exerted as compression and is generally sufficient to overcome such tension.

The forces into which the conductor-forces are resolved, are, in any case, such as the insulating members are best adapted to withstand. At the same time the thickness of the insulating material, measured from cap to cap is so great that puncturing cannot occur, since the voltage which would be necessary to puncture the insulation from cap to cap is enormously greater than that which would cause a discharge or flash around the insulation, say from the conductor to one of the uprights. Hence a "flash-around" would occur, and relieve the excessive potential, before a voltage sufficient to puncture the insulation could be reached. Furthermore, the form of the insulating members may be such, for example the cylindrical form shown, with the grooves comparatively shallow, that the insulation will not be broken by the heat or any power arc, that is, the dynamic arc due to the line current following the flash. Such an arc will lengthen itself and finally break by attenua-

tion in the well known way, leaving the insulating structure in condition for service as before.

It is to be understood that the constructions herein specifically shown and described are merely the preferred forms of the invention, and can be modified in various ways without departing from the proper scope of the invention as defined by the following claims.

I claim—

1. An insulating support for high tension conductors, comprising a framed structure having insulating structural members for resolving mechanical forces originating in the conductor into components and connected each to oppose forces substantially in one direction only, as set forth. 70

2. An insulating support for high tension conductors, comprising a framed structure having insulating structural members for resolving mechanical forces originating in the conductors into components and connected to oppose forces substantially of compression only, as set forth. 85

3. An insulating support for high tension conductors, comprising a framed structure having insulating structural members converging toward the conductor and connected each to oppose forces substantially in one direction only, as set forth. 90

4. An insulating support for high tension conductors, comprising a framed structure having insulating structural members for resolving mechanical forces originating in the conductor into components, conductor-carrying means, and connections between the said means and the said insulating members, constructed to transmit to the respective members substantially only forces in one direction, as set forth. 100

5. An insulating support for high tension conductors, comprising centrally placed means for carrying the conductor, insulating members converging toward said means, and yielding connections between said means and the said insulating members, as set forth. 110

6. An insulating support for high tension conductors, comprising horizontal and vertical insulating members converging toward the conductor, and means for connecting the conductor with the said insulating members, as set forth. 115

7. An insulating support for high tension conductors, comprising a plurality of insulating members arranged to resolve mechanical forces originating in the conductor into components, and means for yieldingly supporting said members, as set forth. 120

8. An insulating support for high tension conductors, comprising a plurality of supporting members, a conductor-carrying device, and a plurality of insulating members yieldingly connected with said supporting- 125

130

members and said conductor-carrying device, as set forth.

9. An insulating support for high tension conductors, comprising a plurality of supporting members, a plurality of insulating members each yieldingly connected at one end with a supporting member, and means for connecting the insulating members at their other ends with the conductor, as set forth.

10. An insulating support for high tension conductors, comprising a plurality of upright supporting members, a plurality of insulating members extending diagonally inward from said upright members, conductor carrying means connected with the

said insulating members at their inner ends, and a vertical insulating member below said conductor carrying means, as set forth.

11. An insulating support for high tension conductors, comprising a plurality of insulating members extending horizontally from the conductor on each side thereof, means for connecting the said members with the conductor at their adjacent ends, and means for supporting the said members at their outer ends, as set forth.

RALPH D. MERSHON.
